Primary Examiner — Leanne Was-Englehart*Assistant Examiner* — Alison Davis(74) *Attorney, Agent, or Firm* — Cooper Legal Group, LLC(57) **CLAIM**

The ornamental design for a data processing equipment, as shown and described.

DESCRIPTION

FIG. 1 is a top, front, and right side perspective view of a data processing equipment showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the data processing equipment that form no part of the claimed design.

1 Claim, 7 Drawing Sheets(56)
